MEANS AND APPARATUS FOR REMOVING AND PREVENTING SCALE INCRUSTATIONS

Application filed April 19, 1926. Serial No. 103,079.

This invention relates to new and useful improvements in method and apparatus for removing and preventing scale incrustations in boilers and other fluid containers subjected to differential temperatures.

In my copending application filed November 21, 1925, Serial No. 70,544, I have described at length the theory of scale incrustation in boilers and similar structures, and I have disclosed a novel method and means for counteracting and nullifying these scale forming activities and for removing scale incrustations that have already been formed. It is therefore deemed not necessary in the present application to repeat this explanation and it is thought that a brief statement will suffice.

It should be added here, however, that it is now known that there is developed a well defined "rectifying" propensity by any boiler, when alternating currents are made use of as a counteracting agency. The theory advanced for this phenomenon is here given for what it is worth and not as a dogmatic assertion that is wholly scientifically correct.

All boilers when in operation generate on their own account a definite direct current which is due to the combination of metals in the boiler, the chemicals in the water content, and the application of heat. This thermo-electrically generated current, of course, is unidirectional at all times. In the case of the alternating current, a periodic reversal of the direction of current flow takes place naturally and according to the frequency of the current used. It is obvious then that when an alternating current is made to flow through the same plane or area, as that of the unidirectional thermo-current of the boiler, the inevitable result is that by reason of the combination of the characteristics of the alternating current, there is a resultant current which is "pulsating" in character, and sets up a more violent electro-magnetic agitation of the scale matter coming into the boiler with the feed-water supply than could otherwise be done with the use of direct current alone, as the medium of counteracting the electro-magnetic effects of the thermo-electrically generated current of the boiler.

Instruments inserted in the circuits during normal operating conditions of the boiler, to which my method is applied, indicate that the "rectifying" effects of the alternating current used may be brought about by any one or all of a number of reasons, to-wit, the phenomenon of "rectification" may be due wholly to the presence of the "unidirectional" thermo-electrically generated current in the boiler, which effectually stops or minimizes one-half of the alternating current wave form whenever or during the instant of the cycle of this A. C. wave is in opposition to the flow of the unidirectional, or thermo-current, or, the phenomenon may be due to an electrolytic or condenser effect of the water and metallic content of the boiler. The manner in which the "wrecking effect" on the scale matter is brought about is accomplished by combining the natural characteristics of both D. C. and A. C. These explanations are offered as possible reasons for the phenomenon of "rectification" and the resultant pulsating current.

The formation of scale is the result of electro-chemical action produced during the operation of the boiler by the action of a local self-generated thermo-electric current which causes the scale particles contained in the water to be deposited or plated on metallic surfaces of the boiler plates or tubes.

This self-generated or local electric current is active so long as the boiler or container is in operation (or is subjected to differential temperatures) and new scale matter is constantly introduced thereinto by the admission of fresh feed water. It is obvious that the plating or depositing of the scale on the metallic surface will go on continuously unless the action of this self-generated current is counteracted, or nullified, or changed into pulsating current, or the fresh feed water treated electrolytically, or electro-magnetically, or both, so as to destroy the attractive force of the self-generated current to plate or deposit scale matter onto the surfaces of the boiler or container.

In the present invention this is accomplished by subjecting fresh feed water to the effects of an externally supplied electric cur-

rent, either by bringing the feed water into contact with electrically charged surfaces of a distributing element or by causing it to traverse an electro-magnetic field by the combination of both. In this manner, normal atomic arrangement of the fresh feed water is disturbed and the electro-chemical propensities of the scale matter contained in solution therein are neutralized by demagnetization and the self-generated local current of the boiler is rendered ineffective to continue its scaling activities. In addition this local current may be counteracted by passing an externally supplied electric current 10 through the container and water content thereof, either by means of an independent current or by connecting said container in series with the feed water energizing circuit.

It is also the object of the present invention to provide an improved form of distributor in the boiler to more effectively distribute the externally supplied electric current through the water content of the boiler 20 whereby all of the water contained therein is subjected to the effects of such externally supplied electric current and efficient circulation thereof through the boiler structure or through the water, or both, is thus assured.

Further objects of the invention are to provide an improved form of a distributor which is highly efficient in operation and of simple construction so that it may be readily 30 assembled and placed in position.

Other objects of the invention are to provide a novel method of treating the feed water electrically before its admission to the boiler, whereby the deposit of the scale matter, contained in the water, onto the metallic surfaces of the boiler is stopped and said scale matter is precipitated in loose form in the boiler or in a separator or precipitating chamber located externally of the boiler so 40 that such precipitated scale matter may be easily removed. The treatment of fresh feed water before its admission to the boiler is particularly desirable in cases where it is impractical or undesirable on account of the size or particular construction of the boiler to locate the distributor within said boiler. However, this method of treating the fresh feed water before it is discharged into the boiler may be used in correlation with the 50 distributors within the boiler if so desired.

Still other objects of the invention are to provide a separator in the feed pipe connection and electrical means for treating the water traversing said separator, whereby the scale matter contained in the water is precipitated in said separator and prevented from entering the boiler. This separator being so constructed that the precipitated scale matter may be readily removed from the 60 separator through suitable connections.

Additional objects of the invention are to provide a plurality of electrodes or distributors arranged in the locomotive boiler and the feed water pipe connection thereof, respectively, and to provide electric circuits for said distributors, said circuits being controlled by the injector so as to open and close said circuits in a predetermined relation with the operation of said injector.

With these and other objects in view, my invention consists in certain novel features of construction and arrangement of parts, hereinafter more fully described and claimed, and illustrated in the accompanying drawings, in which—

Figure 1 is a longitudinal cross section through a conventional type of boiler containing the distributor of my improved form and showing diagrammatically a circuit for supplying current thereto.

Figure 2 is a transverse section taken on line 2—2 of Figure 1.

Figure 3 is a longitudinal cross section through the boiler showing a modified form of my invention.

Figure 4 is a similar view showing another modified form of my invention.

Figure 5 is a longitudinal cross section through a fresh feed water section illustrating the method of treating fresh water electromagnetically.

Figure 6 is a similar cross section showing a distributor arranged in said feed pipe section for treating the water electrolytically.

Figure 7 is a longitudinal cross section through the discharge end of the feed pipe section located in the boiler.

Figure 8 is a vertical transverse section taken on line 8—8 of Figure 7.

Figure 9 is a perspective detail view of one of the insulators used to insulate the distributor from the discharge end of the feed pipe.

Figure 10 is a diagrammatic view showing my improved method for treating the fresh feed water electromagnetically before the admission to the boiler.

Figure 11 is a similar view showing the fresh feed water treated both electrolytically and electromagnetically independently of the boiler.

Figure 12 is a vertical section of the separator or scale precipitating member.

Figure 13 is a diagrammatic view showing my invention applied to a locomotive boiler.

Figure 14 is a detail view of the injector mechanism showing switch means for controlling the circuits of the distributors of the boiler and the fresh water feed pipe.

Referring by numerals to the accompanying drawings and more particularly to Figures 1 to 12, inclusive, 10 indicates an apparatus or metallic container equipped with my invention, said apparatus being in the present instance in the form of a drum 11 shown in Figures 1 and 2 provided with headers 12, 130

tubes 13, and blow-out pipes 14. The water is supplied to the boiler by a feed pipe connection 15, the discharge end 16 of which terminates in the boiler a suitable distance above the bottom thereof and is provided with a 5 T-connection 17. The oppositely disposed ends of this connection have secured thereto short tubular sections or nipples 18 on which are mounted reduced ends 19 of distributor supports 20 carrying distributors 21. 10 Each distributor 21 is connected by a connection 22 to a plug 24 which is mounted in the shell of the drum 11 and is insulated therefrom. lug 24 extends outwardly through the shell and in the form shown in Figures 1 and 15 2, one of the plugs is connected by a connection 25 to one of the terminals of a primary coil 26 of a transformer T, while the other terminal of said coil is connected to one of the main lines 27. The other plug is connected by a connection 28 to the other end of supply lines 27, thereby completing the circuit between said supply lines 27, primary coil 26, and distributors 21. The latter being arranged in the discharge passageways of the feed pipe connection 15, the fresh water before being discharged into the boiler comes in contact with distributors 21 and thereby completes the circuit of the primary coil 26 20 and at the same time is subjected to electrolytic treatment causing the scale matter contained in the fresh feed water to be precipitated in the bottom of the boiler so that the water content of the boiler is free from scale matter. 25

In the form shown in Figures 1 and 2, the secondary coil 26^a has one terminal connected by a connection 29 to the metal shell of the boiler as indicated at 30, and the other terminal of secondary coil 26^a is connected by a connection 31 to a comparatively cool portion of the boiler, namely, blow-out pipe 14, as indicated at 32. In this manner, electrical circuit is established between the secondary coil 26^a and the metallic parts of the apparatus, thereby keeping the metallic surfaces coming in contact with the water charged with an electric current of comparatively large volume, thereby preventing pitting of the metallic surfaces and counteracting the scale tendencies of the natural or self-generated current produced by the operating conditions of the boiler. Thus a two-fold protection is afforded to the apparatus, 45 first, by treating the feed water, as it is being fed in comparatively small quantities to the boiler and before it is discharged thereinto, by an electric current of relatively high pressure which affects the scale matter contained 50 in the water and causes it to be separated from the water and precipitated in loose form in the bottom of the boiler, and, second, by an electric current of large volume and low pressure with which the metallic surfaces 55 of the apparatus coming in contact

with the water are charged and which prevents any combined electro-chemical action between the scale matter and the metallic surfaces so that said scale matter is prevented from being plated onto said surfaces. 70

In the form shown in Figure 3, plugs 24 are connected by connections 34 to the respective terminals of a secondary coil 35 of a transformer T and the terminals of the primary coil 35^a are connected by connection 36 to the respective supply lines 27. In this manner, the distributors or electrodes 21 are connected in circuit with the secondary coil of the transformer and the fresh feed water is subjected to the effects of an electric current if large volume and low pressure. The metallic portions of the boilers are not connected with the supply lines and only the fresh feed water is subjected to the electrical treatment. 80

In the form shown in Figure 4, feed water pipe section 15 is provided with an enlarged portion 37 which forms a core for an electro-magnet or solenoid 38. One terminal of this electro-magnet is connected by a connection 39 to one of the plugs 24 and the other terminal of said electro-magnet is connected by a connection 40 to one of the terminals of a secondary coil 35 of transformer T, while the other terminal of said coil is connected by a connection 41 to the other plug 24. Thus the electro-magnet 38 is placed in series with the distributors 21 and the fresh feed water in passing through pipe connection 15 passes through the hollow core 37 and is acted upon magnetically by the electro-magnetic force of the electric current before coming in contact with distributors 21 in the boiler 11. The magnetic force created by coil 38 affects the scale matter contained in the fresh water and causes the minute particles of the scale matter to coagulate and be precipitated either in the hollow core 37 or in the boiler 11 upon discharge of the feed water in said boiler. 100

By this method the separation of the scale matter from the water is facilitated and is rendered more positive without increasing appreciably the installation or operating costs thereof. 110

This magnetic separator is shown in detail in Figure 5 and consists of reducers 42 which are secured to the respective sections of feed pipe 15 and have connected thereto a tubular member 43 which is of comparatively large diameter and forms a precipitating chamber and the hollow core of electro-magnet 38. Coils 38 are preferably insulated from member 43 by an insulating sleeve 44. 115

The fresh feed water discharge member 20 120 is shown in detail in Figures 7 and 8 and consists of a semi-cylindrical or trough extension 20^a having laterally presented horizontally disposed flanges or ears 20^b. A semi-cylindrical cover 45 fits over trough exten- 125

65 faces of the apparatus coming in contact

sion 20^a and is provided with horizontally disposed flanges 46 adapted to be arranged adjacent to flanges 20^b. Suitable fastening devices such as bolts 47 and nuts 48 are used to engage flanges 46 and 20^b and secure member 45 in position on the trough extension 20^a. The distributor 21, which is preferably tubular in cross section, is removably mounted in position therein by means of insulating blocks 49 which are arranged in seats 50 formed in members 45 and 20^a and space and insulate distributor 21 from said members.

Each distributor is provided with a pair of pins 51 which extend diametrically through said distributor and have their ends projecting therefrom and entering bores 52 formed in blocks 49, whereby the distributor 21 is held against movement relative to said blocks, while the latter are locked against accidental 20 displacement by seats 50.

In this manner a construction is provided which is inexpensive and which can be easily assembled and disassembled to permit removal and replacement of distributor 21. At 25 the same time each distributor is efficiently insulated from members 20 and offers very little resistance to the discharge of fresh water therethrough.

In order to provide for thorough electro- 30 magnetic treatment of the fresh feed water and permit efficient separation of the scale matter from said water, a form of separator or precipitating member such as shown at 54 in Figures 10 to 12 may be used. In this 35 form the member 54 which is of cylindrical shape is disposed vertically between the two feed water pipes 15 and is provided in its upper end with inlet port 55 and outlet port 56 for receiving the respective sections of 40 feed water pipe connection 15. Depending from the top wall of the member 54 is a partition wall 57 which extends transversely between the inlet and outlet ports and terminates a suitable distance above the bottom 45 to 54^a. The latter is preferably concave in cross section to form a sediment chamber for receiving the precipitated scale matter, and leading from the lowermost portion of said bottom wall is a blow-out pipe 58 controlled 50 by a valve 59 whereby the scale matter may be discharged from member 54 through said pipe connection 58.

A coil 38^a is arranged exteriorly on member 54 and produces the magnetic field 55 through which the fresh feed water is caused to travel. The feed water upon being admitted to member 54 through port 55 is deflected downwardly by partition wall 57 into the lower portion of member 54 and is then 60 caused to travel upwardly toward the outlet port 56. In this manner, the water is placed under the magnetic influence for a suitable length of time and the scale matter precipitated by the action of the magnetic force is 65 allowed to gravitate to the bottom of the

separator and is collected a suitable distance below the outlet port 56 so as to prevent it from entering said outlet port. The precipitated scale matter may be readily removed from the separator 54 through pipe connection 58 by opening valve 59, whereby the pressure from the boiler and the feed pump will combine to wash out the contents of the separator through pipe 58.

If desired, the fresh feed water may be 45 treated electrolytically before being admitted to separator 54 for magnetic treatment by placing a distributor or electrode 60 ahead of separator 54 as shown in Figure 11. This electrode is arranged in the enlarged section 61 which is interposed in feed pipe section 15^a and said electrode is secured in position in said section and insulated therefrom by suitable fastening means 62. One terminal of wire connection 64 is secured to one of the supporting plugs 62 and the other terminal of said connection is connected to one of the supply lines 27. The section 61 has connected thereto one of the terminals of wire connection 65 and the opposite end is connected to the other end of supply lines 27 so that the circuit is completed by the water contained in section 61 and contacting with said section and with the distributor 60.

If desired, electro-magnet 54 may be energized by connection 65 as shown in Figure 11. By this arrangement the fresh feed water is first subjected to electrolytic treatment so as to act on the scale matter contained in the water and the water is then subjected to electromagnetic treatment to complete the precipitation of the scale matter. By this arrangement, the fresh feed water may be treated to remove scale matter therefrom before its admission to the boiler whereby it may be unnecessary to further treat the water in the boiler. Such arrangement may be particularly desirable in constructions where it is not convenient to place the distributors in the boiler.

In the treatment of fresh feed water for locomotive boilers, the fresh feed water may be treated alternately with the water in the boiler as shown diagrammatically in Figure 13. Owing to the practice of pumping the feed water into the locomotive boiler intermittently by a pumping device of the injector type, there are as a natural consequence periods of time when the injector 66 is not working and consequently fresh feed water 120 is not being fed to the boiler. In order to provide for this, a suitable two-way switch 67 is operable in conjunction with the injector 66 to control in correlation with said injector a circuit 68 of a distributor 69 arranged in locomotive boiler 70 and a circuit 71 of a distributor 72 which latter is arranged in an enlarged section 73 of feed water pipe 74, which latter furnishes the 125 fresh feed water to boiler 70, and is controlled 130

5 by injector 66. Circuit 68 is connected to a stationary contact 75 and circuit 71 is connected to a stationary contact 76 by a switch 67. These contacts are adapted to be engaged by a blade 77 which is fixed to and insulated from lever 66^a of injector 66 and is connected by a connection 78 to one pole of an electric generator 79, the opposite pole of which is connected by connection 80 to the shell of boiler 70. Plate 77 is operable by 10 operating handle 66^a to engage contact 76 and complete the circuit of distributor 72, when injector 66 is operated to feed fresh water through pipe connection 74 to boiler 70 so that distributor 72 is energized and the 15 fresh feed water is subjected to electrolytic or electro-magnetic treatment or both.

When injector handle 66^a is actuated to stop the flow of fresh water, blade 77 is disengaged from contact 76 and is brought into 20 engagement with contact 75 whereby the circuit of distributor 69 is completed to energize the latter and treat the water contained in the boiler.

25 From this it will be seen that during the period of operation of the injector, the switch 67 is set to divert the electrical current of the generator 79 to the treatment of the feed water by energizing distributor 72 and 30 during the periods of time when the injector 66 is inactive and not pumping feed water into the boiler 70. Switch 67 is operated to divert the electrical current of the generator 79 to the exclusive treatment of the water 35 content of the boiler by means of energizing distributor 69 which is arranged in boiler 70.

Either direct or alternating current may be used for magnetically treating the water. When the electric current is used to charge 40 the boiler shell and the water contained therein, I prefer to use alternating current as the effect of the latter on the natural or self-generated current has tendency to render the scale removing and preventing operation 45 more efficient.

The location of magnetically charged separators in the feed pipe connection whereby the fresh feed water is compelled to traverse the magnetic field affects the scale matter 50 contained in the water, magnetically and causes said scale matter to settle in the lower end of the separator, thereby preventing said scale matter from entering the container or boiler. The separator is so constructed that 55 the accumulated scale matter may be readily discharged therefrom without the necessity of stopping the operation of the boiler. The advantages of such arrangement are of great value in the practical operation of boilers and 60 will be readily apparent to anybody conversant with the present practice of power stations and other plants.

While I have shown and described the preferred embodiment of my invention, it is 65 obvious that my invention may be used in

various combinations with various forms of boilers, evaporators, condensers, and other containers, and that various changes may be made in the construction and arrangement of parts of my apparatus without departing 70 from the spirit of my invention.

I claim:

1. In an apparatus for preventing scale incrustation in boilers and the like, the combination with a boiler and a pipe connection 75 for supplying feed water thereto, of a source of alternating current supply, a distributor section disposed in the open end of said feed water pipe connection and insulated therefrom, and electrical connections for connecting said source of alternating current supply 80 with said distributor and the water passing therethrough.

2. In an apparatus of the class described, the combination with a boiler, of a feed water 85 pipe having two spaced outlets disposed therein, a distributor arranged adjacent to and insulated from each outlet, and an external electric circuit having its terminals connected to the respective distributors, 90 whereby the feed water discharged from said outlets completes said circuit and is thereby subjected to the electrolytic action of the electric current.

3. In an apparatus of the class described, 95 the combination with a boiler, of a feed water pipe terminating within said boiler in a pair of spaced outlets, a distributor secured within and insulated from each outlet, a source of alternating electric energy, and an electric 100 circuit having its terminals connected to the respective distributors and insulated from said boiler and said feed water pipe, whereby the water discharged from said outlet completes said circuit and is thereby subjected 105 to the action of an alternating current.

4. In an apparatus of the class described, the combination with a boiler and a feed water supply pipe therefor, of a discharge 110 end disposed within said boiler and secured to said feed water pipe and provided with a pair of spaced outlets, a tubular distributor arranged in each outlet in spaced insulated relation therewith, and an external electric circuit having its terminals connected to the 115 respective distributors and insulated from said feed water pipe and said boiler, whereby said circuit is completed by the water discharged through said outlets and causes said water to be subjected to electrolytic action. 120

In testimony whereof I hereunto affix my signature this 12th day of April, 1926.

GEORGE SPENCER NEELEY.
